DESCRIPTION

1. Tyre tread
- 1.1 : Perspective
- 1.2 : Perspective
- 1.3 : Front
- 1.4 : Left
- 1.5 : Right
- 1.6 : Enlarged
- 1.7 : Enlarged
- 1.8 : Enlarged
- 1.9 : Cross sectional
- 1.10 : Cross sectional

Fig. 1.6 is a fragmentary enlarged perspective view surrounded by line 1-1 and line 1'-1' in Fig. 1.1; Fig. 1.7 is a fragmentary enlarged front view surrounded by line 2-2 and line 2'-2' in Fig. 1.2; Fig. 1.8 is a fragmentary enlarged front view surrounded by line 3-3 and line 3'-3' in Fig. 1.3; Figs. 1.9 and 1.10 are cross-section views taken along lines A-A and B-B in Fig. 1.8 respectively; in the drawings, the pattern repeats uniformly throughout the circumference of the tyre tread, and broken lines depict environmental subject matter only and form no part of the claimed design.
